United States Patent Office

Des. 222,961

Patented Feb. 15, 1972

222,961

PACKAGING CUP OR THE LIKE

Bryant Edwards, Clarendon Hills, Ill., assignor to Illinois Tool Works Inc., Chicago, Ill.

Filed Mar. 12, 1970, Ser. No. 21,880

Term of patent 14 years

Int. Cl. D9—03

U.S. Cl. D9—216

Fig. 1

Fig. 2

Fig. 3

FIG. 1 is a side elevational view of a packaging cup or the like showing my new design;

FIG. 2 is a top plan view; and

FIG. 3 is a bottom plan view thereof.

I claim:

The ornamental design for a packaging cup or the like, as shown.
